LAMP HOLDER FOR PIN BASE TUBULAR LAMPS

Filed March 9, 1948

UNITED STATES PATENT OFFICE

2,502,994

LAMP HOLDER FOR PIN BASE TUBULAR LAMPS

Arthur A. Richardson, Edgewood, R. I., assignor to Harry M. Burt and Guy H. Burt, doing business as The Lloyd Products Company, Providence, R. I.

Application March 9, 1948, Serial No. 13,819

11 Claims. (Cl. 173—328)

1

This invention relates to lamp holders for pin base tubular lamps. More particularly the invention pertains to lamp holders which are adapted to individually support and supply power to the ends of an electric illuminating device such as a fluorescent lamp by coaction with the projecting contact pins on the ends thereof.

The lamp holder is characterized by its ability to swing towards and away from an end of the fluorescent lamp and by the presence of a biasing mechanism for urging the lamp holder into coupling engagement with the projecting contact pins. Lamp holders of this general character are shown and described in United States Letters Patent No. 2,403,968 issued to Charles E. Dansereau on June 16, 1946.

It is an object of the present invention to provide a lamp holder of the character described which is an improvement over the lamp holders shown in the aforesaid Letters Patent.

More specifically, it is an object of the present invention to provide a lamp holder of the character described which is of stubby configuration being thereby adapted to be employed in a shallow space wherein a lamp holder with an elongated body such as shown in said Letters Patent will not fit.

In the above connection, it is an ancillary object of my invention to provide a lamp holder of the character described which is adapted to be mounted directly on a surface faced by an end of the lamp, rather than on a surface above or below the lamp (it being assumed that the lamp is horizontally disposed as is the lamp holder shown in said Letters Patent).

It is another object of the invention to provide a lamp holder of the character described which comprises very few parts, although the same is of a strong and durable construction.

More particularly, it is an object of the invention to provide a lamp holder of the character described in which the various parts are so constructed as to perform dual functions so that, although the lamp holder has all of the requisite operating characteristics of the lamp holder shown and described in said Letters Patent, it has less parts.

In general a lamp holder of the type shown and described in said Letters Patent includes five different kinds of parts, each having its own function. There are: a support member which is designed to be mounted on an electric fixture or the like, a socket member which is designed to receive the lamp pins, a pivoting means for pivotally attaching the socket member to the sup-

port member, contact means designed to engage the lamp pins, and a biasing means for resiliently urging the socket member toward the lamp. According to a feature of the present invention, the functions of certain of these parts are combined. More specifically, a lamp holder according to the present invention has mating portions of the socket and support members acting as the pivoting means, and incorporates the function of the biasing means in the contact means.

It is a more limited object of the invention to provide a lamp holder of the character described in which the support and socket members are so constructed that they can be pivotally interfitted, and in which the contact means lock said two members together against any relative movement except the desired pivotal one.

It is yet another object of the invention to provide a lamp holder of the character described in which the support and socket members and the contact means, despite their multiple functions, can be assembled with ease and by comparatively unskilled labor.

It is a further object of the invention to provide a lamp holder of the character described in which the different parts are of comparatively simple construction so that the lamp holder can be manufactured and sold at a low cost.

It is an additional object of the invention to provide a lamp holder of the character described which will simplify wiring and assembly of electric fixtures.

It is yet a further object of the invention to provide a lamp holder of the character described in which the contact means acts as a strain relief.

It is still a further object of the invention to provide a lamp holder of the character described in which the lamp pins can be inserted and removed easily.

Other objects of the invention will in part be obvious and in part will be pointed out hereinafter.

The invention accordingly consists in the features of construction, combinations of elements, and arrangements of parts which will be exemplified in the constructions hereinafter described and of which the scope of application will be indicated in the appended claims.

In the accompanying drawings in which are shown various possible embodiments of the invention:

Fig. 1 is a side elevational view of a pair of lamp holders embodying the invention, the same being mounted on the walls of an electric fixture

2

which face the ends of a fluorescent electric discharge lamp;

Fig. 2 is an enlarged sectional view taken substantially along the line 2—2 of Fig. 1, the same constituting a front or face view of one of the lamp holders;

Fig. 3 is a vertical central sectional view through the lamp holder, the same being taken substantially along the line 3—3 of Fig. 2;

Fig. 4 is a horizontal central sectional view through the lamp holder, the same being taken substantially along the line 4—4 of Fig. 3;

Fig. 5 is a vertical view through the lamp holder at one of the lamp pin channels, the same being taken substantially along the line 5—5 of Fig. 2;

Fig. 6 is a view similar to Fig. 5, but illustrating the lamp holder as it appears when swung outward during insertion of a lamp;

Fig. 7 is a front view of the mounting member as it appears when the socket member has been removed;

Fig. 8 is a top view of the mounting member;

Fig. 9 is a back view of the socket member as it appears when removed from the mounting member;

Fig. 10 is a perspective view of a contact as it appears apart from the mounting and socket members; and

Figs. 11 and 12 are views similar to Figs. 5 and 10, respectively, of a lamp holder embodying a modified form of the invention.

Referring now in detail to the drawings, and more particularly to Figs. 1 through 10, the reference numeral 20 denotes a conventional fluorescent electric discharge lamp mounted by means of a pair of lamp holders 22, 24 between a pair of opposed walls 26, 28 which may, for example comprise the opposite end walls of a lighting fixture. The lamps are of the incandescent filament type, and each has a pair of projecting contact pins 29 on both ends thereof which, as is usual in the lighting field, are adapted to be coupled removably with the lamp holders 22, 24 to provide electric power and physical support for the lamp. Both of the lamp holders are of identical construction so that only one lamp holder will be described in detail.

Said lamp holder essentially includes only three kinds of parts. These are: a mounting member 30, a body or socket member 32, and a contact member 34.

The mounting member 30, which preferably is molded from a plastic electrically non-conductive material, and desirably from a thermo-setting material, such for instance as a phenol-formaldehyde condensation product, comprises a block, the surface of which facing the lamp is formed with a deep recess 36. The lower end of this recess opens through the bottom wall of the block. The upper end of the recess terminates short of the top wall of the block (see Fig. 7). However, a portion of said top wall is undercut to provide a passageway 38 providing access to the base of the recess 36 through said top wall. Due to this construction, the top wall of the block in the vicinity of the recess 36 comprises a bridging bar 40 located on the front surface of said block.

The two side walls 42, 44 of the recess 36 extend vertically and are flat and parallel to one another. The base wall 46 of the recess is provided with a pair of broad shallow indentations 48, 50, one adjacent each side wall 44, 42 respectively. The bottom ends of said indentations are defined by low flanges 52 forming shoulders 54

(see Fig. 5). The upper ends of said indentations are defined by another set of flanges 56. These flanges may be provided with cut away portions 58 approximately large enough and deep enough to accommodate one half of a conventional lead-in wire for the lamp holder. Two through apertures 60 pierce the base wall of the recess 36, one of these apertures being located in each of the shallow indentations. These apertures each are large enough to pass a lamp holder lead-in wire. The block also includes a pair of downwardly projecting toes 62 on opposite sides of the recess 36, said toes having their front surfaces flush with the front surface of the block, and their rear surfaces inset from the rear surface of the block as best seen in Figs. 1 and 8. In addition to the foregoing, the block is fashioned with a pair of front-to-back through bores 64 whose forward ends are located in notches 66.

The various openings, recesses and the like, above described with respect to the mounting member, have divers functions which will become apparent as this description proceeds.

The socket or body member 32 preferably is molded from an electrically non-conductive material similar to that employed for fabricating the mounting member. Said socket likewise comprises a block fabricated to a certain desirable shape. The block is somewhat elongated vertically as seen in Fig. 9. It has a central portion 68 of its front face which is flat, this portion being designed to be substantially flush with the front surface of the mounting member when the lamp holder has a lamp end disposed against the same (see Fig. 5). The upper end of the socket member has an integral upstanding flange 70 set back from the front face. This flange is adapted to extend through the passageway 38 and is slightly narrower than the passageway so that it is able to rock therein. The front wall of the flange slopes rearwardly to a slight extent in a downward direction whereby to limit to a very narrow area (in effect, a line), the pivotal contact between this wall and the front wall of the passageway 38 and thus reduce the frictional force opposing rocking of the socket member.

The socket member has a pair of deep indentations 72 running downwardly from approximately the horizontal center thereof, said indentations being disposed on opposite sides of the socket, and, in effect, constituting lateral setbacks. That is to say, one wall of each indentation is lacking. The indentations run down from laterally disposed notches 74 which extend in a front-to-back direction through the socket. The lower ends of the indentations 72 have their base walls sloping toward the rear surface of the lamp holder as best seen in Fig. 5. In addition, the indentations converge toward one another as they approach the bottom tip 75 of the socket. In the aforesaid region where the indentations converge, the front face of the socket slopes toward the rear of the lamp holder, said sloping portion being indicated by the numeral 76.

The flat central portion 68 of the front face of the socket is approximately equal in height to the vertical dimension of the recess 36 beneath the bar 40, and the width of the socket is just slightly less than the width of said recess, so that said socket member can be freely received in the recess and yet will substantially fill the same. The depth of the socket member is somewhat less than the depth of the recess, but it soon will be seen that means is provided to bias the socket

member toward its outward position wherein its front face is substantially coplanar with the front face of the mounting member. Moreover, the height of the flange 70 is substantially equal to that of the bar 40 (see Fig. 3) so that this flange will not protrude noticeably above the mounting member.

When the socket member is disposed within the recess 36 with the flange 70 located in the passageway 38, said socket member is free to rock from a forward position such as illustrated in Fig. 5, to a rearward position such as illustrated in Fig. 6, the rocking taking place about the upper forward edge 78 of the flange 70. When the socket member is located in the recess 36, the notches 72 will have their open outer sides closed by the side walls 42, 44 of the recess 36, and these same side walls will complete the notches 74. In addition, the lower portion of the socket member, and principally the part co-extensive with the rearwardly sloping portion 76, will protrude beneath the main part of the mounting member which terminates at the bases of the toes 62. The socket member includes a pair of wings 80 wider than the balance of the socket member, said wings being adapted to abut against the back faces of the toes 62 so as to limit the forward motion of the socket member. The rearward motion of the socket member is limited by abutment of the back wall of said socket member against the flange 52.

From the foregoing it will be appreciated that the socket member and mounting member are so mutually constructed as to jointly provide a relative pivoting action, and it therefore is not necessary to employ an additional member or mechanism to function as a pivot relative to which the support and socket member can oscillate.

Two contact members 34 are employed, each being formed from resilient electrically conductive sheet metal stock. Each contact member includes a shank 82 and leg 84 which are formed in one piece, being joined to one another by a 180° return bend 86 so that the shank and leg are parallel if not stressed. Optionally, and as illustrated herein, the leg 84 is slotted as at 88 from its free end all the way back to the shank, thus dividing the leg into two parallel elements. This arrangement is employed to increase the flexibility of the legs and for another purpose which will later be pointed out.

The two contact members are disposed in the recess 36, the shank 82 of each being located in a different one of the shallow indentations 48, 50, and being disposed substantially flat against the base wall of such indentation (see Fig. 5). The bend 86 and leg 84 are located within troughs 90 fashioned in the back surface of the socket member. Two such troughs are provided, one for the leg 84 of each contact member, and the troughs are separated by a thin partition 92. The contact members are fashioned to such dimensions that, when the socket member fills the recess 36 and the lower edge of the shank 82 is abutted against the shoulder 54, the top of the bend 86 rests against the upper wall 94 of the trough 90. This wall is substantially perpendicular to the back surface of the socket member. Such arrangement and dimensioning of the contact members prevents a socket member from slipping out in a downward direction from the position in which it fills the recess 36. In other words, the contact members act as locking means for captively holding the socket member within the mounting member. Said locking means, how-

ever, due to the provision of the bend 86 and the resilient material from which the contact members are fabricated, does not prevent pivotal movement of the socket member relative to the mounting member about the flange 70 and bar 40.

Moreover, due to the resilient nature of the contact member and the fact that, if unconstrained, the leg 84 and shank 82 are parallel to one another, said contact members serve to bias the socket member to its forward position in which the wings 82 abut against the back of the toes 62. It is to obtain such resilient biasing action that the wall 96 of the trough is sloped rearwardly, thus deflecting the leg 84 from its unconstrained position shown in Fig. 10. The lower edges of said legs 84 terminate at the bottom edge 98 of the trough so that said legs lie immediately in back of the through notches 74 whereby the legs are in position to be electrically engaged by the tips of the lamp contact pins 29. Due to the fact that said leg is slotted, only one of its elements will be engaged and depressed by a lamp pin as seen in Figs. 4 and 5. Thus, there is no danger of the bend 86 being distorted to such an extent that it will permit any downward movement whatsoever of the socket member.

The various parts of the lamp holder are assembled and used as follows: A pair of contact members are placed in the shallow indentations 48, 50. Then the socket member 32 is introduced into the recess 36 and the flange 70 directed toward the passageway 38 while the socket member is held inclined with respect to the mounting member. The socket member then is pressed down to force the bends 86 of the two contacts into the troughs 90. As the flange 70 enters the passageway 38 the two contact members will be pushed rearwardly until the free ends of the shanks 82 snap over the shoulders 54 and fully into the shallow indentations 48, 50. Thereupon, the socket member and mounting member will be locked together and cannot be taken apart except by the use of special fixtures which enable the contact members to have their shanks and legs flexed towards one another while at the same time the socket member is rocked and pulled in a direction away from the passageway 38.

Inasmuch as the lamp holder cannot be taken apart in the field, the same is provided with lead-in wires 100 by the manufacturer. These lead-in wires have the insulation stripped from one end thereof to expose the central conductor which is secured to a contact member permanently in suitable fashion. Because of the relatively small size of the lamp holder, and the small space in which the contact members are designed to fit, the lead wires herein are shown as soldered to the contact members (see Fig. 10). In the first described form of my invention each contact member is provided with a through opening 102 in its shank through which the lead-in wire passes. Thus, the portion 104 of the lead wire which is designed to be employed to connect the lamp holder in an electric circuit extends perpendicularly away from the back of the shank 82. Said lead-in wire emerges from the lamp holder through one of the openings 60.

In the modified form of my invention shown in Figs. 11 and 12, the lamp holder 165 is identical to the lamp holder 22 described with respect to Figs. 1-10. However, the lead-in wires instead of coming out of the back of the socket through the openings 60 leave through the top of the socket passing through the cut away portions 58. See Figs. 7 and 8. It will be observed that the

back surface of the socket member 32 is provided with cut away portions 106 to match the cut away portions 58 and provide full size passageways for the lead-in wires. Conveniently, the lead-in wires 100 in the form of the invention shown in Figs. 11 and 12 may pass through the slots 88 in the contact member.

In both forms of the invention the lamp holder is held in place by attaching means such as long shank screws 108 which pass through the openings 64.

It thus will be seen that I have provided lamp holders which achieve the several objects of my invention and are well adapted to meet the conditions of practical use.

As various possible embodiments might be made of the above invention, and as various changes might be made in the embodiments above set forth, it will be understood that all matter contained herein is to be interpreted as illustrative and not in a limiting sense.

Having thus described my invention, I claim as new and desire to secure by Letters Patent:

1. A lamp holder of the character described for mounting on a support a lamp having at least one contact pin at each end thereof, said lamp holder comprising a mounting member adapted to be secured to a support, a socket member, cooperating means on said socket member and said mounting member for pivotally interengaging said socket member and mounting member, and a contact member lying between said mounting member and said socket member, said contact member being located in a position transversely offset from the axis of rotation of the pivotal engagement, said contact member being resilient and bearing against said mounting member and socket member so as to urge the same apart, said socket member having an aperture therein to receive a pin at one end of the lamp, said aperture extending through said socket member to said contact member so that said contact member can touch a lamp pin in said aperture.

2. A lamp holder as set forth in claim 1 wherein the cooperating means on the socket member and the mounting member for pivotally interengaging said members comprises a flange carried by one of said members and an opening in the other member into which the flange extends, said member carrying the flange having an abutment adjacent the flange which bears against the other member adjacent the opening, the surfaces of both said members which face one another having indentations therein in which portions of the contact member are seated whereby relative movement of said first two mentioned members in a direction withdrawing the flange from the opening is prevented.

3. A lamp holder as set forth in claim 1 wherein a portion of the contact member rests against an abutment on the mounting member and another portion of the contact member rests against an abutment on the socket member, said abutments being spaced apart in a direction perpendicular to the axis of rotation of the pivotal interengaging means whereby the contact member captively secures the socket member and mounting member together.

4. A lamp holder of the character described for mounting on a support a lamp having at least one contact pin at each end thereof, said lamp holder comprising a mounting member adapted to be secured to a support, said mounting member having a deep recess in the front face thereof, a socket member in said recess, cooperating means

on said socket member and said mounting member for pivotally interengaging said socket member and mounting member, and a contact member disposed in said recess and lying between said mounting member and said socket member, said contact member being located in a position transversely offset from the axis of rotation of the pivotal engagement, said contact member being resilient and bearing against said mounting member and socket member so as to urge the same apart, said socket member having an aperture therein to receive a pin at one end of the lamp, said aperture extending through said socket member to said contact member so that said contact member can touch a lamp pin in said aperture.

5. A lamp holder as set forth in claim 4 wherein in the socket member and mounting member are provided with cooperating abutment means which limit the outward movement of the socket member away from the mounting member.

6. A lamp holder as set forth in claim 4 wherein in the socket member and mounting member are provided with cooperating abutment means which limit the outward movement of the socket member away from the mounting member and wherein in the contact member is under compression when said abutting means contact one another.

7. A lamp holder as set forth in claim 4 wherein in the socket member and mounting member are provided with cooperating abutment means which limit the outward movement of the socket member away from the mounting member and wherein in the front face of the socket member is approximately flush with the front face of the mounting member when said abutting means contact one another.

8. A lamp holder as set forth in claim 4 wherein a portion of the contact member rests against an abutment on the mounting member and another portion of the contact member rests against an abutment on the socket member, said abutments being spaced apart in a direction perpendicular to the axis of rotation of the pivotal interengaging means whereby the contact member captively secures the socket member and mounting member together.

9. A lamp holder as set forth in claim 4 wherein in a portion of the contact member rests against an abutment on the mounting member and another portion of the contact member rests against an abutment on the socket member, said abutments being spaced apart in a direction perpendicular to the axis of rotation of the pivotal interengaging means, the abutment member on the socket member being closer to said axis than the abutment member on the mounting member, whereby the contact member captively secures the socket member and mounting member together.

10. A lamp holder as set forth in claim 4 wherein in the interengaging means for effecting relative pivotal movement of the socket member and mounting member comprises a bar across one end of the recess and a projection on the associated end of the mounting member extending through the space under the bar.

11. A lamp holder as set forth in claim 4 wherein in the cooperating means on the socket member and the mounting member for pivotally interengaging said members comprises a flange carried by one of said members and an opening in the other member into which the flange extends, said member carrying the flange having an abutment adjacent the flange which bears against the other member adjacent the opening, the surfaces of both said members which face one another hav-

ing indentations therein in which portions of the contact member are seated whereby relative movement of said first two mentioned members in a direction withdrawing the flange from the opening is prevented.
